TIE HANGER

Walter H. Sorensen, Rte. 11, Box 160H,
San Antonio, Tex. 78213

Filed Feb. 8, 1967, Ser. No. 5,723

Term of patent 14 years

(Cl. D80—8)

Fig. 1

Fig. 2

Fig. 3

FIGURE 1 is a perspective of a tie hanger showing my new design;

FIGURE 2 is a front elevational view thereof; and

FIGURE 3 is an elevational view taken from one side thereof.

The broken line representation of a garment hanger and a tie in FIGURE 1 is for purposes of illustration only. I claim:

The ornamental design for a tie hanger, as shown and described.
